UNITED STATES PATENT OFFICE

154,499

DESIGN FOR A SWEATER OR SIMILAR ARTICLE

Samuel Levine, New York, N. Y.

Application August 4, 1948, Serial No. 147,931

Term of patent 3½ years

(Cl. D3—4)

To all whom it may concern:

Be it known that I, Samuel Levine, a citizen of the United States of America, residing in New York, county of New York, and State of New York, have invented a new, original, and ornamental Design for a Sweater or Similar Article, of which the following is a specification, reference being had to the accompanying drawing, forming part thereof.

The figure is a front view of a sweater or similar article showing my new design. The rear view of the sweater is conventional.

The dominant feature of my design resides in the portions shown in solid lines.

I claim:

The ornamental design for a sweater or similar article, substantially as shown and described.
SAMUEL LEVINE.
